UNITED STATES PATENT OFFICE

ARTHUR WILLARD RANGER, OF LONDON, ENGLAND

PLATEN PRINTING PRESS

Application filed August 2, 1930, Serial No. 472,658, and in Great Britain January 27, 1930.

The invention relates to platen presses in which the sheets are carried from a pile to the platen, held there during the printing operation, removed after printing and delivered by means of radial arms—usually two—provided with grippers, the arms rotating intermittently, for example, through 90° at each operation.

To obtain perfect registration with such mechanism is extremely difficult and the slightest irregularity in the mechanism determining the position of each gripper arm on the platen or irregularity in the stacking of the sheets, on the pile, or unequal wear of mechanism driving the gripper arms will interfere with the registration, as no means integral with the platen are provided for definitely registering the sheet.

The present invention insures accurate registration irrespective of the above difficulties, and it is characterized therein that the grippers are adapted to release each sheet momentarily while it is on the platen prior to the printing operation, and that registration of the released sheet is then effected by means of one or more lays which are adapted to be moved to engage with the sheet and thereby set it in a determined position where it remains during the printing operation.

The known means may be adopted for intermittently rotating the radial gripper arms to bring the sheets on to the platen and to remove the printed sheets therefrom, and the known mechanism may be used to open and close the grippers, such mechanism, however, being modified so as to effect an additional opening of the grippers of the radial gripper arm which is for the time being over the platen in order to release the sheet and to permit of it being set into correct registration by the lay or lays.

The lay or lays are so arranged, for example, they may be so moved before the depositing of a sheet on the platen and after the registering and printing thereof, that they allow each gripper arm to move on to, over and away from the platen, the grippers seizing the printed sheet and carrying it away and delivering it in the usual manner.

Thus the registration of the sheets is ef-

fected by means which are independent of the gripper arms, so that slight variations in the positions of the gripper arms, or in the relation of the sheets to them when carried to the platen, have no effect on the registration. 55

The invention is further characterized by the provision of means whereby the lay registering mechanism can be thrown out of action at the will of the operator. This 60 is useful when the invention is applied to a platen press which sometimes may have to be used for printing several sheets at a time or on other work which does not require perfect registration. 65

The accompanying drawings illustrate an example of lay registering mechanism for a platen press according to the invention.

Figure 1 is a plan (as seen when looking perpendicular to the plane of the platen) of the platen with radial gripper arm mechanism and the registering lays. 70

Figure 2 is a plan partly in section showing part of the main shaft and the cams thereon for operating the gripper opening 75 and closing mechanism and for operating the lays.

Figure 3 is a view, on a larger scale, of part of the lay mechanism.

Figure 4 is a side view corresponding to 80 Figures 1 and 2.

Figure 5 is a cross section of one gripper arm and the side lay.

Figure 6 is a plan of part of a gripper blade. 85

Figure 7 is a view (seen when looking perpendicular to the platen) illustrating mechanism for rendering the lay registering mechanism inoperative.

Figure 8 being a corresponding plan of the 90 upper portion of same.

Figures 9 and 10 are, respectively, a side view and a view, seen when looking perpendicular to the platen, of modified mechanism 95 for operating the registering lays.

Figures 11 and 12 are sectional views illustrating two examples of fine adjustment devices for the lays.

Figure 13 is a sectional side view illustrating another form of lay. 100

The invention is illustrated as applied to a platen press in which two grippers arms 1, 1, are mounted on a carrier 2 fixed to a shaft 3 and rotated intermittently through 90°, the gripper arms 1, passing successively over the platen 4 to bring sheets thereon and to remove the printed sheets therefrom. Each gripper arm 1 has the usual slotted gripper blade 5 for gripping the sheet between it and the sharp edge 6, except that the slots 7 preferably have bevelled edges 8 to avoid the corners of the sheet catching in these edges.

It is assumed that the intermittent rotation of the shaft 3 is effected as usual by bevel gearing in a gear case 9, the operating shaft 38 of these gears being driven in the usual manner from the main shaft of the machine. These parts being well known, there is no necessity to illustrate them.

The gripper blades 5 are opened intermittently by a cam 10 freely mounted on the shaft 3 and oscillated by a slotted cam 11, Figure 4, on the main shaft 12, through the medium of a bell crank lever 13 which is pivoted at 14, has a pin or roller 15, in the slotted cam 11 and is pivotally connected at 16 to a rod 17 which is pivotally connected at 18 to an arm 19 fixed to the cam 10.

Each gripper blade 5 is mounted on a hinge pin 20 which has an arm 21 pivotally connected at 22 to a rod 23 which is pivotally connected at 24 to a lever 25 which has a pivot pin 26 freely mounted in the carrier 2 and has a lever 27 provided with a roller 28 engaged by the gripper opening cam 10. A spring 29 tends to close the gripper blades 5. It is coiled about a rod 30 which passes through studs 31 pivotally mounted on the levers 25.

This is known mechanism for opening and closing the gripper blades, but in order that the gripper blades shall be opened to release each sheet momentarily while it is on the platen immediately before registration is effected and shall close again to remove the printed sheet from the platen, the usual oscillatory gripper opening cam 10 has an additional rise 32 and the usual slotted cam 11, Figure 4, for oscillating the oscillatory cam 10, has an additional rise 33. The rise 33 thus gives the required additional oscillation to the cam 10 and the rise 32 opens the gripper blades of that gripper arm which is at the platen.

In order to register the sheet when so released momentarily on the platen 4 a side lay 34 and bottom lays 35 are provided to engage respectively with the side and bottom edges of the released sheet.

The side lay 34 is fixed on a shaft 36, Figure 3, which is free to oscillate in a bearing 37 which is cast on the side of the platen 4 and a bracket 39 which is fixed by screws 40 to the side of the platen. A collar 41 and a bevel wheel 51 prevent endwise movement

of the shaft 36. A coiled spring 43 rotates the shaft 36 in one direction to hold the side 34 against a fixed stop such as a stud 44 which is screwed into the side of the platen 4.

The bottom lays 35 are fixed on a shaft 45 which is mounted to oscillate in the bracket 39 and in a bearing 46 which is fixed by screws 47 to the platen 4. A spring 48 rotates the shaft in one direction until the shaft is arrested by a stop so as to hold the bottom lays 35 adjacent to the bottom edge of the platen 4. Each bottom lay 35 preferably has a light spring blade 49 for engagement with the face of the sheet. A stiffer blade 96 prevents undue yielding of the blade 49.

In the example shown in Figures 1 to 4, the two shafts 36 and 45 are connected by toothed bevel wheels 50, 51, to ensure that the side lays 34 and bottom lays 35 shall be operated in unison. The shaft 45 has a crank 52 having a roller 53 which is engaged intermittently with a cam 88 on a rocking lever 54 which is pivoted at 55 and is held by a spring 56 with its roller 57 in engagement with a cam 58 on the main shaft 12. The crank 52 has a lug 90 for engagement with the bracket 39 to act as the stop above referred to for arresting the bottom lays in the registering position.

As a sheet is brought on to the platen 4 by one of the gripper arms 1, into an approximate printing position, the additional rise 33 on the slotted cam 11 and the additional rise 32 on the gripper opening cam 10 effect the momentary release of the sheet. Meanwhile the cam 58 has allowed the side lay 34 and the bottom lays 35 to move towards the platen under the action of the springs 43, 48, to engage with the side and bottom edges of the released sheet and thereby set it accurately in its correct printing position, that is, to register the sheet correctly. It is advisable to allow a certain amount of back lash (clearance) between the teeth of the bevel wheels 50 and 51 to allow the side and bottom lays to be firmly pressed by their springs into registering position in the event of one reaching that position before the other.

It will be appreciated that the lay mechanism described is independent of the mechanism which rotates the gripper arms so that inaccuracies in this latter mechanism have no effect on the registration of the sheet which is perfectly affected by the lays.

The sheet is accurately registered by the lays and is held by them during the printing operation. After the printing has been effected, the additional rise 32 has left the roller 28 and allows the gripper blades to grip the sheet again to remove it from the platen after the printing operation and deposit it on a pile in the usual manner. It will be understood that the cam 58 through

the medium of the rocking lever 54 and crank 52 rotates the lay shafts 36 and 45 to remove the lays 34, 35 from the platen before the sheet is removed therefrom.

5 When it is desired that the platen press may be used for printing on several sheets simultaneously and with work which does not require accurate registration, means are provided by which the lay mechanism may 10 be rendered inoperative. An example of such means is illustrated by Figures 7 and 8 wherein the additional rise 32 of the gripper opening cam 10 is secured to a block 59 which is pivoted on a pin 60 on the side boss 15 of the cam. The block 59 also has a projection 61.

When the block 59 is in the position shown against a stop pin 76, the additional rise 32 is in the operative position over the cam 10. 20 When the block is turned about the pin 60 through 90°, the rise 32 is in an inoperative position away from the cam 10 and the projection 61 engages under the segment 62 which is formed on a lever 63 which is pivoted at 64. The segment 62 has a handle 65 by which it can be raised slightly to permit of the projection 61 being placed under it. The lever 63 is slotted at 66 to receive a pin 67 on the end of the rod 68 guided in a lug 69 and having a blade 70 at its lower end. A spring 71 is interposed between the lever 63 and a collar 72 on the rod 68.

When the projection 61 is set under the segment 62, the lever 63 depresses the rod 61 35 and the blade 70 engages in a slot 73 in the collar 41 when the side lay 34 is moved away from the platen, the blade 70 then preventing the lay shaft 36 rotating under the action of its spring 43, Figure 3, when the 40 lever 54 releases the roller 53. Consequently the lays 34 and 35 will not be operated.

Figures 9 and 10 illustrate a modification of the lay operating mechanism. In this example the bottom shaft 45 is operated by 45 the crank 52, roller 53, a cam 88 and lever 54, as in the example above described, but the side lay shaft has a bevel wheel 74 meshing with a bevel wheel 75 which is fixed on a spindle 84 mounted in a boss 85 on the 50 bracket 39, the spindle 84 having a crank 86 provided with a roller 87 which is engaged by a cam 89 on the lever 54.

By these means the side lay and the bottom 55 lays are independent of each other and may be timed to move one in advance of the other instead of simultaneously by suitably shaping the cams 88 and 89. This may be advantageous with sheets of certain shape and size.

60 Fine adjustment devices may be fitted on the lays to determine or vary the final registering positions of the lays. For example, in Figure 11 the side lay 34 is provided with a finely threaded screw 77 which abuts 65 against the edge of the platen 4 (or against

the stop 44, Figure 3). The screw 77 has a collar 78 and the spaces between the collar 78 and the head of the screw and the adjacent sides of the lay 34 allow for a certain adjustment.

70 Figure 12 shows an example of adjustable bottom lay. The lay 35 has a spring 79 fixed at 80 to the lay. It carries a light bow spring 81 for engaging with the face of the sheet. The shoulder 82 of the spring 79 75 engages with the edge of the sheet. A finely threaded set screw 83 affords adjustment of the spring 79 and, therefore, of its shoulder 82.

75 It sometimes happens (especially when 80 dealing with very thin sheets of paper) that the bottom edge of the sheet sags or curls over the lower edge of the platen owing to its momentum at the moment the gripper arm stops with the sheet over the platen. 85 This results in the edge of the paper buckling as it is not in a position to be engaged properly by the bottom lays and, therefore, it is desired that the lower edge of the sheet shall be supported and, if necessary, 90 straightened out just prior to the registration.

95 In order to avoid the bottom edge of a sheet sagging or curling over the bottom edge of the platen, such as might occur with 100 a very thin sheet of paper owing to its momentum at the moment a gripper arm is arrested with a sheet over the platen, each bottom lay 35 may be provided with a light spring blade 91, Figure 13, which is always 105 in contact with the edge of the platen and yields as the lay 35 advances towards the platen.

I claim:

1. In a platen printing press having radial 105 arms provided with grippers and adapted to be partially rotated intermittently in the plane of the swinging platen to bring sheets onto and remove them from the platen, means for releasing each sheet from the grippers momentarily when at the platen and means for registering each sheet when so released including lays adjacent to the side and bottom edges of the platen and means for moving said lays relatively to the platen.

110 2. In a platen printing press having radial arms provided with grippers and adapted to be partially rotated intermittently in the plane of the swinging platen to bring sheets onto and remove them from the platen, an oscillatory cam for opening and closing said grippers and a rotary cam for oscillating said oscillatory cam, additional rises on said cams for effecting an opening and closing of the grippers while at the platen, lays adjacent to said platen and means for moving said lays relatively to said platen for the purpose of registering each sheet when the grippers are open while at the platen, substantially as 115 hereinbefore set forth.

3. In a platen press having gripper opening and closing means and lays for registering each sheet on the platen as claimed in claim 2, means for holding the lays in inoperative positions, and an additional rise, on the oscillatory cam for opening and closing the grippers of each arm while at the platen, which is adapted to be moved out of its operative position relatively to the gripper opening and closing mechanism and into a position to operate said means for holding the lays in inoperative positions substantially as and for the purpose hereinbefore set forth.
4. In a platen press having radial arms, intermittently rotated in the plane of the swinging platen, provided with grippers for bringing sheets onto and off the platen, means for opening and closing the grippers of each arm when at the platen, lays adjacent to the side and bottom edges of the platen, means including springs for moving said lays towards the platen when the grippers at the platen are open, means for arresting said lays in determined positions when so moved, and means for moving said lays away from the platen against the action of said spring, substantially as and for the purpose hereinbefore set forth.
5. In a platen press having radial arms, intermittently rotated in the plane of the swinging platen, provided with grippers for bringing sheets onto and off the platen, means for opening and closing the grippers of each arm when at the platen, lays adjacent to the side and bottom edges of the platen, means including springs for moving said lays towards the platen when the grippers at the platen are open, adjustable means for arresting said lays in determined positions when so moved, and means for moving said lays away from the platen against the action of said spring, substantially as and for the purpose hereinbefore set forth.
6. In a platen press having radial arms, intermittently rotated in the plane of the swinging platen, provided with grippers for bringing sheets onto and off the platen, means for opening and closing the grippers of each arm when at the platen, shafts adjacent to the side and bottom edges of the platen, lays on said shafts, springs for rotating said shafts to move the lays towards the platen when the grippers at the platen are open, and means for rotating said shafts against the action of said springs to move the lays away from the platen, substantially as and for the purpose hereinbefore set forth.

In testimony whereof I have signed my name to this specification.

60 ARTHUR WILLARD RANGER.
